Attorney

UNITED STATES PATENT OFFICE.

JAMES H. SPEED AND FRANK DEVAULT, OF CLARKSTON, WASHINGTON.

BAG-HOLDER.

1,260,086.

Specification of Letters Patent. Patented Mar. 19, 1918.

Application filed August 15, 1917. Serial No. 186,339.

To all whom it may concern:

Be it known that we, JAMES H. SPEED and FRANK DEVAULT, citizens of the United States, residing at Clarkston, in the county 5 of Asotin and State of Washington, have invented certain new and useful Improvements in Bag-Holders, of which the following is a specification.

This invention relates to bag holding devices and it is the principal object of the invention to provide a bag holder especially adapted for arrangement upon the discharge spouts of threshing machines and other mills, whereby a bag or sack will be properly held free of the ground until filled, thereby maintaining the sack distended and doing away with the jiggling of the same by hand to insure filling thereof.

Another object of the invention is to provide a bag holder which when the bag held thereby is completely filled, will be lowered and deposited on the ground, thus eliminating lifting of the same from the holder.

A further object of the invention is to provide the bag holder with clamping jaws which will enable a bag or sack to be easily and quickly engaged thereby in a manner such as to prevent tearing of the sack.

It is also an object of the invention to provide a bag holder of such construction as to insure the uniform filling of bags engaged therewith.

The improvements in the details and arrangement of parts will be apparent from an inspection of the accompanying drawings, in connection with the specific description hereinafter contained, and wherein the preferred embodiment of the invention is disclosed for the purpose of imparting a full 40 understanding of the same.

In the drawings:—

Figure 1 is a side elevation of the improved bag holder;

Fig. 2 is an end elevation thereof;

Fig. 3 is a top of the same; and

Fig. 4 is a fragmentary detail in perspective showing the relation of the clamping elements of the bag holder.

Similar characters of reference refer to 50 similar parts throughout the several views of the drawings.

Having more particular reference to the drawings, 1 represents a sectional clamping collar which is adapted to be engaged with 55 the discharge spout of a threshing machine or other mill. Bearings are arranged at

diametrically opposite points upon the sides of the sectional collar and are designated by the numeral 2.

Vertically disposed standards 3 are slidably received through the bearings 2 and are formed with series of openings 4 adapted to receive a bearing pin 5 therein. A washer 6 is arranged upon each of the uprights 3 and rests normally upon the upper faces of the 65 bearings 2, serving as means for receiving the lower convolutions of expandable coiled springs 7 which are arranged about the several standards 3 and have their upper ends engaged with the several bearing pins 5. 70 The lower ends of each of the standards 3 are bifurcated and extended laterally as at 8; the said lateral portions having clamp- 75 ing jaws 9 formed upon their outer extremities and lying parallel to each other.

Substantially U-shaped brackets 10 are rotatably received in bearing collars 11 carried upon the lower portions of the standards 3 beneath their respective bearings 2. A yoke 12 having its opposite sides extending longitudinally of and arranged parallel to the clamping jaws 9 is provided and is pivotally engaged with the extremities of the U-shaped brackets 10 as at 13. By so connecting the yoke 12 with the brackets 10 80 it will be seen that the sides of said yoke may be swung downwardly to positions adjacent the clamping jaws 9, thus affording means whereby the sides of a bag or sack may be efficiently gripped therebetween. To 85 insure snug engagement between the clamping jaws 9 and the sides of the yoke 12, a curved guide member 14 is secured to each of the said jaws 9, and obviously, receive the sides of the yoke 12 therebetween.

To facilitate moving of the yoke 12, a handle 15 is arranged upon the rear portion thereof.

In operation, the sides of a bag are arranged over the clamping jaws 9 and the 100 edges folded downwardly thereupon. The yoke member 12 is now forced downwardly by grasping the handle 15 and pressing the same forwardly. When in this position, the sides of the yoke member 12 will lie adjacent the clamping jaws 9 and as a consequence, the sides of the bag or sack will be securely held therebetween. The cut-off means arranged in the spout or other discharge means to which the clamping collar 110 1 is attached may be now opened. As the bag is gradually filled with matter, the

weight of the same will accordingly increase and due to the manner in which the clamping jaws 9 are supported through the medium of the standards 3 and the coiled springs 7, the bag will be permitted to gradually lower onto the ground. When the bag has been completely filled, the yoke member 12 is pulled upwardly, thereby releasing the sides of the bag from between the 10 sides of the same and the clamping jaws 9.

It is to be noted, that a bag when held by my improved holder will be maintained in distended position at all times. Therefore, jiggling of the same by hand will be unnecessary. Further, the tension of the 15 springs 7 may be adjusted so as to cause the filling of the bag to a predetermined point.

Manifestly, the construction shown is capable of considerable modification and 20 such modification as is within the scope of our claims, we consider within the spirit of our invention.

We claim:

1. In a bag holder, a clamping collar having diametrically disposed bearings arranged thereon, clamping jaws slidably received in said bearings, a yoke, means for pivotally supporting the yoke with relation to said jaws, and a handle secured to the yoke.
2. In a bag holder, a clamping collar having bearings arranged upon the opposite sides thereof, jaws slidably received and re-

silently supported in said bearings, a yoke, means for pivotally supporting the yoke with relation to said jaws, and a handle secured to the yoke.

3. In a bag holder, a clamping collar having bearings arranged upon the opposite sides thereof, standards slidably received by said bearings, coiled springs arranged about the upper portions of said standards and having engagement with said bearings, the lower ends of said standards being provided with laterally extended clamping jaws, a yoke, means for pivotally supporting the yoke with relation to said jaws, and a handle arranged on the yoke.

4. In a bag holder, a clamping collar having an apertured ear arranged upon the opposite sides thereof, standards slidably received through said ear, expansible coiled springs arranged about the upper portions of said standards and bearing on the ear, the lower end of said standards being bifurcated and carrying clamping jaws upon their outer ends, a yoke having the sides thereof arranged parallel to said clamping jaws, means for pivotally supporting the yoke with relation to said jaws, and a handle on the yoke.

In testimony whereof, we affix our signatures hereto.

JAMES H. SPEED.
FRANK DEVAULT.
